UNITED STATES PATENT OFFICE.

HARVEY BROWN, OF BUFFALO, NEW YORK, ASSIGNOR OF ONE-HALF TO ALOYSIUS H. SCHAEFER, OF BUFFALO, NEW YORK.

KEYHOLE GUARD.

Application filed September 15, 1921. Serial No. 500,739.

To all whom it may concern:

Be it known that I, HARVEY BROWN, a citizen of the United States, residing at Buffalo, in the county of Erie and State of New York, have invented certain new and useful Improvements in Keyhole Guards, of which the following is a specification.

My invention relates to improvements in key-hole guards, and it has for its primary object the provision of an improved device adapted to be applied to the key-hole of a door so as to prevent the removal of the key from the outer side of the door.

Another object of my invention is the production of a simple, inexpensive, and highly effective device for the purpose stated which can be easily applied to and as readily detached from the door.

A still further object is to provide a key-hole guard which, when placed within a key-hole of a door, can neither be drawn outward or forced inward from the outer side of the door, and which can be retained in the rectangular lower portion of a key hole even though the key is held in the key-hole in a manner to permit the locking or unlocking of the door.

A still further object is the provision of an improved key-hole guard which will prevent the turning of a key into a position to permit removal of the key from either side of the door.

With the above and other objects in view to appear hereinafter, my invention consists in a device adapted to be inserted into a key-hole of a door after the insertion of a key therein, with a view of preventing the removal of the key therefrom, thereby guarding against the surreptitious entrance of burglars or others into a room through the use of a duplicate or "skeleton" key, or the use of lock-picking tools.

In its more limited sense, the invention consists in the novel features of construction and in the arrangement and combination of the integral parts thereof to be hereinafter described and more particularly pointed out in certain of the appended claims.

In the drawings:—

Fig. 1 is a perspective view of a portion of a door and the adjacent portion of the door casing, showing my improved key-hole guard inserted into the key-hole of the door.

Fig. 2 is a horizontal section through the door and a portion of the door-casing, taken

in a plane passing through the key-hole, the locking mechanism within the lock casing being omitted.

Fig. 3 is a section taken on line 3—3, Fig. 2.

Fig. 4 is a perspective view of my key-hole guard.

Having reference to the drawings in detail, the numeral 5 designates a door, 6 the outer escutcheon, and 7 the inner escutcheon. The escutcheons are applied in any suitable manner to the outer and inner faces of the door and each has a key-hole opening 8 therein which forms part of a key-hole 9 that extends through the door proper and through the lock mortised into the door, and of which latter only the lock-casing 10 is shown.

It is, of course, to be understood that my device is adapted for use in any kind of key-hole, as a lock applied to one side of a door is often used, instead of a mortise-lock. Therefore, where hereinafter the term "key-hole" is employed, it may mean any hole or opening in a door into which a key is to be inserted, regardless of the location or construction of the locking-mechanism.

When a lock is applied to one side of a door, it is applied to the inner, or that side of the door facing the room the lock is to protect, and in such cases, an escutcheon is applied to the outer side only.

The door 5 closes against a door stop 11 on or secured to the door jamb 12 to which a locking plate 13 is secured which has an opening into which the lock-bolt of the locking-mechanism (not shown) is adapted to be projected when locking the door.

My improved key-hole guard considered as a whole is designated by the numeral 14 and it is constructed of a flat strip of springy material bent midlength upon itself, as at 15, to form two arms 16, 17, which bear against each other along a portion of their lengths and are thence separated, as at 18, so that their outer portions 19 yield to pressure and are therefore capable of being pressed together, or at least of being moved toward each other. The inner portion of the device, which may be referred to as the guard portion, is comparatively rigid or non-yielding while the outer portion formed by the separated parts of the arms 16, 17 are flexible, and may be referred to as the lock portion.

The arms 16, 17, have stop prongs 20, 21, preferably formed by stamping a U-shaped incision in each arm and bending the metal bounded by the incision outwardly. The 5 prong of one arm is preferably out of line with that of the other, so that when inserting the guard into a keyhole, the prong 20 will be positioned at the inner side of the inner escutcheon and the prong 21 at the outer side 10 thereof, both at marginal portions of the key-hole as clearly shown in Fig. 2. When inserting the guard into the key-hole, it is of course necessary to press the spaced outer portions 19 of the two arms together, or at 15 least toward each other, so that the stop prong 20, which is adapted to be positioned at the inner side of the escutcheon, will clear the wall of the key-hole opening 8 in the latter, and when positioned in a plane 20 passing in rear of the escutcheon, the flexible outer portions of the arms may be allowed to spread, whereupon the stop prong 20 will move into a position behind the escutcheon while the stop prong 21 will move in front 25 of said escutcheon.

Any efforts made on the part of a burglar or other person to surreptitiously withdraw the guard from the key-hole will be frustrated, since the stop prong 20 will prevent 30 inward movement of the guard while the prong 21 prevents outward movement thereof. On account of the oblong cross-section of the guard and by reason of the fact that the flexible outer portions of the arms 16, 17, 35 are held against the walls of the lower rectangular portion of the key-hole opening 8 in the escutcheon, the guard cannot be turned. It is, therefore, impossible to remove the guard from the outer side of the 40 door, and it is consequently impossible to open the door from the outside by means of a duplicate or "skeleton" key or any other tool.

In cases where a lock is fastened to the

inner side of a door, my improved guard is 45 inserted directly into and through the lock, with the lock prong 20 positioned against the inner side of the outer wall of the lock and the lock prong 21 against the outer side of 50 said wall. That portion of the guard extending through the lock being entered in that portion of the key-hole formed in the door to the extent necessary to properly position said lock prongs as stated.

From the foregoing it will be clear that 55 the guard may be retained in the key-hole of the door even though the key is inserted therein; also that the key may be turned either to lock or unlock the door. The key cannot, however, be withdrawn from the 60 key-hole until the guard has been removed, which is readily done by pressing the outer portions 19 of the guard together, or at least toward each other, and then pulling the guard bodily from the key-hole.

Having thus described my invention, what I claim is:—

1. A guard for key-holes having escutcheons, comprising a guard portion and integral springy arms at one end of said guard portion having outer free ends and lock prongs extending laterally therefrom in different planes, said prongs being adapted to engage opposite sides of an escutcheon at marginal portions of its key-hole.

2. A guard for key-holes formed of a flexible strip of metal bent medially upon itself to form two arms lying in contact with each other a portion of their lengths and being spaced apart along the remainder of their 80 lengths to form free-ended spring lock portions, each spring lock portion having a lock prong stamped laterally therefrom and said lock prongs being at different points along the length of said guard.

In testimony whereof I affix my signature.

HARVEY BROWN.
